UNITED STATES PATENT OFFICE.

LIZZIE H. DICKELMAN, OF FOREST, OHIO.

FRAME WITH ADJUSTABLE AND REPLACEABLE SASH FOR CONVERTIBLE GRAIN BINS
AND BROODER HOUSES.

Application filed June 1, 1925. Serial No. 33,875.

My invention has for its object to provide a sash and supporting frame that are so constructed that they may be readily secured in a building, particularly, a sheet metal construction, and so that the sash may be easily removed and replaced by other sashes, such as, a sash having glass may be replaced by a sash having muslin or fabric extending across and secured at its edges to the sash, or a sash having a sheet metal covering, according to the results to be produced or the use to which the building is to be put. The invention also provides for adjusting the sash to obtain desired ventilation and retain the sash in its adjusted position.

The sash may be used in constructions of different forms but I have found that the sash is of particular advantage when used in brooder houses to obtain the desired warmth, light and ventilation. In the preferred form of construction, the sash is used in cylindrical sheet metal buildings that are designed for fall and winter storage of grain and in the spring may be most efficiently used for brooding chicks. Thus by my invention the conversion may be made from one to the other, and if desired ventilation may be obtained for the grain when it is used as a grain crib, and when used as a brooder house, the invention will provide the required light, ventilation and temperature to produce the conditions that are not only required for the raising and brooding of chicks, but also provides means whereby these conditions may be regulated to greatly decrease the mortality of the chicks. To present a practical application of the invention, I have selected as an example of structure containing the invention, a convertible grain crib and brooder house, and shall describe it hereinafter. The convertible structure is shown in the accompanying drawings.

Figure 1 of the drawings is a side view of a convertible grain bin and brooder house, a part being shown in section to more clearly illustrate the construction of the building. Fig. 2 illustrates an enlarged view of a section of a part of the window frame and a part of the sash. Fig. 3 illustrates the sash and the window frame, and shows, particularly, the manner in which the lower part of the sash may be raised, while the upper part of the sash is open to secure ventilation through the bottom as well as through the top of the frame. Fig. 4 illustrates a cloth

or muslin sash located in the window frame in place of the glass sash shown in Figs. 2 and 3. Fig. 5 is a view of a section of the sash and the frame taken on the line 5—5 indicated in Fig. 4. Fig. 6 is a view of a sash having a sheet metal covering that closes the opening through the frame and is provided with ventilated openings for permitting the air to enter and pass through the grain to the central ventilating shaft that may extend to the top of the structure to cause the air to pass through the grain and out through the roof ventilator.

The invention is particularly applicable to sash frames where it is found desirable to replace the frames according to the result that it is desired to obtain as to ventilation, light and heat, and as to the contents or the purpose for which the building is to be used. My invention thus provides a removable sash that may be covered and form a frame for sheet materials of different kinds, such as glass, fabric, or sheet metal according to the uses to which the structure is to be put, and according to the results that it is desired to obtain. In the particular form of the invention which is selected as an example of structures containing my invention, and shown in the drawings, the building has a sheet metal cylindrical wall 1, a sectional conical roof 2 and a central ventilator 3. The building can be used as a crib for the storage of grain in the fall and winter and then may be used as a brooder house for brooding chicks. When used as a brooder house the ventilator or part of it may be used as a chimney, and a brooder stove 4 may be connected therewith by means of the pipe 5. A suitable brooder shield or dissipator 6 of heat may be supported above the stove 4, and one or more sashes 7 having glass panes 8 may be inserted in frames 9, permitting the sunlight to enter the building and keep the building warm as the season advances. The sash 7 is moreover so constructed as to produce ventilation in the middle of the warmer days. Also the sash is so constructed that it may be removed and replaced by muslin covered sashes or frames to give the desired day and night ventilation in the still warmer seasons of the year. The sash 7 is formed of two parts 10 and 11 that are hingedly connected together by means of the hinges 12. The parts are rabbed along their juxtaposed edges as at 13, 14

to protect the interior from the weather. Each frame 9 is provided with grooves or channels, extending the length of the sash, for the sash to slide in, with outer flanges 14 and 15. The flange 15 extends from the bottom of the opening of the frame 9 to a point that may be as high as the lower part of the sash, provided the lower part of the sash does not exceed substantially one half 10 the height of the frame. If the part 11 exceeds one half the height of the frame the flange 15 extends upwards to a point that is located below the top of the opening of the frame, a distance substantially the same 15 as the height of the part 11 of the frame, and so that in either case the sash may be readily removed by opening the upper part 10 and raising the sash, the lower part 11 sliding between the guiding flanges 14 and 20 15 until the bottom of the lower part 11 reaches a point near the upper end of the flange 15, whereupon the top of the lower part 11 may be swung inwards and further lifted, if required, to raise the sash to cause 25 the lower end of the part 11 to clear the upper end of the flange 15, which are located on opposite sides of the frame 9. The upper end of the flange 15 being located below the lower end of the part 10 of the sash, the 30 said upper part of the sash may be opened more or less to permit circulation of air through the upper part of the opening in the frame. The extent of the opening may be adjusted by securing the upper end of the 35 upper part 10 of the sash. In the form of construction shown, a chain 16 may be secured to the frame 9 and a hook 17 may be secured to the upper end of the part 10 of the sash. The hook 17 may be secured 40 in any of the links of the chain to adjust the opening at the top of the frame. Also, if desired, the part 10 of the sash may be swung to a point approximating 90° or a little better, and the lower part 11 of the 45 sash may be raised which will increase the ventilation by providing an opening below and above the lower part 11 of the sash as shown in Fig. 3. Below the sash and in the lower part of the frame 9 a sliding door 18 50 may be provided to open and close an opening 19 to allow the chicks to pass in and out of the building.

When it is desired to replace the sash 7 having window panes 8, by a sash frame 55 having muslin, this may be readily done by providing a sash 20 that is constructed substantially the same as the sash 7 but which is covered with cloth or muslin 21 and inserting the sash 20 in place of the sash 7. 60 This is preferably done when the season has advanced so that it is desired to keep the temperature down to the proper degree, and

yet prevent drafts. The muslin frames, however, will provide for the necessary ventilation for the chicks. The sash 20 may 65 be adjusted and readily removed in the same manner that the sash 7 is adjusted and removed.

When the building is to be converted into a corn crib or grain bin for the storage of 70 corn and the like, the muslin covered sash 20 may be removed and a sash 22 having sheet metal panels 23 may be inserted in place of the sash 20. The sheet metal panels 23 may be provided with tongues 24 that 75 are struck out from the sheet metal to form openings 25 to allow the upward and inward movement of air in the manner well known in connection with certain corn crib constructions. This will permit the air to pass 80 through the grain and out through the ventilator 3 of the bin.

In order to readily secure the frame 9 to the sheet metal of which the building is 85 formed, I have provided Z-bars 26 that extend along the side of the frame 9 and are bolted to the frame by means of the bolts 27 that extend through the outermost flanges 28 of the Z-bars 26, and through the sides of the frame. The remaining flanges 29 of the Z-bars 26 may be readily bolted by means of the bolts 30 to the edges of the sheet metal wall 31 of which the structure is formed. If desired, the Z-bars 26 may be so shaped as to be adapted to the change in 90 direction as between the plane of the frame 9 and the plane of the adjoining part of the wall 31 or to the direction of the cylindrical formation of the wall 31 at the opening in the wall in which the frame 9 is located. 100

I claim:

In a house formed of sheet metal, a Z-bar upright, a window frame, means for connecting one flange of the Z-bar to the wall 105 of the house and means for connecting the other flange of the Z-bar with the window frame, a sash having two parts hingedly connected together and supported in the frame, the frame having a groove or channel 110 extending the length of the sash for the sash to slide in, with the outer flange on one side of the groove or channel cut away at a point that is located a distance from the top of the opening of the frame that is slightly greater than the height of the lower 115 part of sash, an adjustable member for securing the upper part of the sash open and so disposed as to secure the lower part in a raised position to produce ventilation through the frame above and below the sash part. 120

In testimony whereof I have hereunto signed my name to this specification.

LIZZIE H. DICKELMAN.
